SUSPENSION MEANS

Jacob I. Robin, New York, N. Y.

Application May 18, 1945, Serial No. 594,537

7 Claims. (Cl. 223—91)

1

The invention relates to suspension means for wearing apparel, curtains, portieres, towels, and a multitude of other articles of domestic use, and, more particularly, to devices of this character wherein the suspended article is held in place by snubbing action between two or more parallel bars.

In a copending application, Ser. No. 533,364, I have disclosed a device of this nature wherein the bottom bar is fixed and the upper bar or bars are movable relatively to the lower bar, being guided in this movement by cords or wires connecting the lower bar to a coat hanger. The upper bar or bars in that device are not removable. In the present invention, they are removable, this feature affording a number of advantages, such as the ability of wrapping the article to be suspended around a removable upper bar and then placing the bar with the wrapped article into its place above the lower bar. This arrangement greatly facilitates the proper suspension of articles which it is difficult to introduce between adjoining bars. When several articles are to be suspended in the device, it is provided with two, three or more movable and removable bars one above the other. The removability of the bars is especially advantageous in such a case, both for the operation of suspension, and for the removal of the garments or other articles, as one of these articles may be removed without disturbing the other suspended articles. When the device includes a coat hanger, trousers or skirts suspended between the bars may be removed without the necessity of first removing the coat. Or, if a collection of towels or neckties is suspended between the bars, it is possible to remove a selected article without dislocating the other suspended articles in any way. The device is also adapted to operate as a display rack or as a drying rack, and for many other functions which it is unnecessary to enumerate and which endow the invention with a great variety of useful applications tending to simplify one's work. It may be added that the simplicity of the device also contributes to the low cost of its manufacture and its availability to a great mass of people at a very low cost.

In the drawing, Figure 1 is a perspective view of a device embodying the present invention and incorporating a coat hanger. Figure 2 is a cross section along the line 2—2 of Figure 1. Figure 3 is a perspective view of a modified form of the device shown in part only. Figure 4 is a cross section along the line 4—4 of Figure 3. Figure 5 is another modification of the device, also shown

2

in part only. Figure 6 is a sectional view of still another modification of the device, shown in part only. In Figures 5 and 6, the coat hanger is omitted.

5 Referring to the Figures 1 and 2 in detail, 1 is a coat hanger provided with a two prong suspension hook made up of a wire 2 bent over the coat hanger and held tight on it by a movable ring 3. From the coat hanger 1, near its ends, 10 hang two brackets 4 and 4' by means of loops 5 passing through holes 6 in the coat hanger. The brackets 4 and 4' are made up of a wire bent into two prongs, one, 7, ending in the loop 5, and the other, 8, passing through holes 11 and 12 in 15 the bars 9 and 10. These bars are parallel to one another, the lower one, 9, being kept in place on the bend of the two prongs 7 and 8. A garment 13 is shown as suspended between the bars 9 and 10, being wrapped around the upper bar 20 10 and held in place by the snubbing action between the two bars.

In Figure 3 is shown a modification of the device, wherein the prongs 7 and 8 are arranged to hold the parallel bars between them without 25 having the prong 8 pass through holes in the bars. In this illustration, three bars are shown instead of the two bars of Figure 1. It is to be understood, however, that in the device shown in Figure 1, also, three or more bars may be used, this 30 remark applying to every one of the illustrations here shown. The three bars 14, 15 and 16 in Figure 3 have grooves 17, the reduced diameter of the bars fitting in between the prongs 7 and 8. As shown in Figure 3, all of the bars are removable, but if it is desired to hold the lowest one 35 in place, any convenient method may be used.

The operation of the device is self evident and it seems entirely superfluous to discuss it except to point out some of its advantages over similar 40 devices of the day. As already stated in the preamble, the main advantage resides in the removability of the bars lying above the stationary lowest bar. How much this feature facilitates the operation of the device must be obvious to anyone who has tried to remove one suspended article from among several held between the bars. It is also important to note that the combination of the bars with a coat hanger is only one of its many uses. The brackets holding the bars may be attached directly to a wall 45 or other support, as is illustrated in Figures 5 and 6. This form of the device is particularly applicable to the use as a towel rack, a drying rack, or as a display rack. When various articles are suspended from a succession of super-

imposed bars, it is easy to remove those on top without dislocating or otherwise disturbing those below. All one has to do is to remove the top bar together with its suspended article. The hooks 18 are provided as an additional means for the suspension of garments provided with straps, such as many kinds of women's wear. Sometimes, it may be desired to divide the bars in the middle, so as to suspend two halves of an article, one on each portion of the bar, as, for instance, when hanging up a set of portieres. This modification is not illustrated as it is an obvious change. When the bar is so divided, each portion can turn on the corresponding prong as an axis and it may be unnecessary to remove the bar. Of course, after the article is suspended, the divided bar is made whole again by any suitable means. Various decorative features may be added to the device.

The illustrations here shown are believed to amply clarify the essential features of the device without a detailed enumeration of the many changes of which the invention is susceptible, within the scope of the appended claims.

Claim:

1. A pair of two-pronged brackets, one prong of each bracket having an open end, means for securing the other prongs of each one of said brackets at a predetermined distance from one another, and a multiplicity of bars arranged one above the other for parallel movement in said brackets and guided by said prongs and entirely removable therefrom, due to said open ends.

2. A suspension device, including a garment hanger, a pair of two-pronged brackets, one prong of each bracket having an open end means for securing the other prongs of each one of said brackets to said hanger proximate its ends, and a multiplicity of bars arranged one above the other for parallel movement in said brackets and guided by said prongs and entirely removable therefrom, due to said open ends.

3. A suspension device, including a coat hanger provided with holes near its ends, a pair of brackets suspended from said coat hanger through said holes, each one of said brackets being formed by bending a length of wire into two prongs and an arc between them, the open end of one of said prongs forming a loop passing through one of said holes in the coat hanger, a multiplicity of parallel bars arranged one above the other between said prongs and provided with holes proximate their ends, the other one of said prongs

passing through said holes in the bars, the bottom bar resting on said arc, and the upper bars being movable along said second prong and entirely removable therefrom.

5. A suspension device, including a coat hanger provided with holes near its ends, a pair of brackets suspended from said coat hanger through said holes, each one of said brackets being formed by bending a length of wire into two prongs and an arc between them, the open end of one of said prongs forming a loop passing through one of said holes in the coat hanger, a multiplicity of parallel bars arranged one above the other between said prongs, said bars being provided with grooves proximate their ends, said prongs fitting into said grooves, the bottom bar resting on said arc, and the upper bars being movable in said grooves between the prongs and entirely removable therefrom.

20. 5. A device according to claim 4, wherein additional suspension means is provided by forming one of the prongs into a hook.

6. A pair of two-prong open end brackets, at a predetermined distance from one another, and a multiplicity of bars arranged one above the other for parallel movement in said brackets and guided by said prongs and entirely removable therefrom, due to said open ends.

7. A suspension device, including a garment hanger, a pair of two-prong open end brackets, means for securing said brackets to said hanger proximate its ends, and a multiplicity of bars arranged one above the other for parallel movement in said brackets and guided by said prongs and entirely removable therefrom, due to said open ends.
